UNITED STATES PATENT OFFICE.

DANA H. BENJAMIN, OF CLEVELAND HEIGHTS, OHIO, ASSIGNOR TO THE AMERICAN LAUNDRY MACHINERY COMPANY, OF CINCINNATI, OHIO, A CORPORATION OF OHIO.

NEGLIGEE-SHIRT PRESS.

Application filed February 23, 1917, Serial No. 150,468. Renewed December 9, 1921. Serial No. 521,249.

This invention relates to shirt pressing machines, and more particularly to machines for pressing negligee or soft shirts. The object of the invention is to provide an improved machine which enables a negligee or soft shirt to be folded into final form or shape, and while stretched and held in proper position, to be pressed as a whole, thereby improving its appearance and enabling the maker to command a higher price for his goods. A further object of the invention is to provide means for stretching and holding the shirt in proper shape or form and arranged to preserve parallel straight side edges on the shirt, together with pressing means which will not injure the shirt buttons and will improve the appearance of the entire shirt. A further object of the invention is to provide automatically actuated means for returning one or more operating members associated with the bed to normal position upon movement of the bed relative to the head, to avoid damage to the parts and for other reasons as will appear.

Further objects of the invention are in part obvious and in part will appear more in detail hereinafter.

The invention comprises the shirt pressing machine hereinafter described and claimed.

In the drawings, Fig. 1 represents a front view of one form of machine embodying the invention; Fig. 2 is a side elevation of one of the work holding tables or pressing members, with a shirt clamped in position thereon; Fig. 3 is a plan view thereof, broken away to expose the several layers; Fig. 4 is an end view from the left in Fig. 40; Fig. 5 is an end view from the right in Fig. 3; Fig. 6 is a detail plan view showing a modification; Fig. 7 is a detail view showing the neckband former; Fig. 8 is a plan view, on a reduced scale, of the stationary pressing member; and Fig. 9 is a similar view of the "hair pin" form on which the shirt is dressed.

The pressing machine shown in the drawings comprises a suitable frame 1 having a hollow base 2, and uprights 3, 4, and a cross head 5. Said cross head supports a stationary pressing member 6, which is preferably a hollow cast metal member having an inner heating chamber connected to a

source of heat such as the steam pipe 7. Said member is of substantially rectangular shape but is provided at one end with a large recess 8 to receive and embrace the shirt neckband, as will later appear, and with two small recesses 9 in its lower face, one on each edge, and on its opposite end carries a rigid arm 10 provided with two friction rollers 11 for a purpose which will appear hereafter.

The upright 3 is a shaft which serves as a support for a rotatable frame 12 which turns freely on said shaft and has oppositely extending arms 13 which support two identical work carrying tables and pressing members indicated at 14, and description of one of which will suffice for both. Each table comprises a body member 15 having a heavy stem or shaft 16 slidable vertically in a sleeve 17 of an arm 13 and held from rotating relative to the swinging frame 12 by a guide pin 18.

Directly beneath the stationary pressing member 6 the hollow base is provided with a vertically slidable actuating plunger 19. When either work table is brought to position under the pressing member 6 its stem 16 is directly over the plunger 19 and by elevating the plunger the work table or lower pressing member is moved into pressing relation with the upper member. Any suitable means may be employed for operating plunger 19, such as a treadle lever or like mechanism or a suitable fluid pressure actuated device. As shown the plunger 19 is connected to a piston working in a cylinder 21 to which fluid pressure, such as compressed air or steam or water or oil under pressure may be supplied by a pipe 22. Suitable means is provided, such as the spring pressed latch 23 controlled by treadle 24, for locking the frame 12 in either of its two working positions with the lower pressing member accurately and properly located beneath the upper or stationary member 6.

The body member 15 of each lower pressing member carries a flat table portion 25, of rectangular form, whose upper surface is covered by a suitable yielding cushion or pad which may consist, for example, of one or more layers 26 of sponge rubber and a cloth cover 27, and on which the shirt to be pressed is laid.

The shirt to be pressed is dressed on a skeleton or "hair pin" form, a number of which may be provided for each machine so that one attendant can dress the shirts on the forms and remove them after the pressing operation, while another attendant will merely manipulate the machine. Each form is made of a flat thin metal sheet having a body portion 28 about as large or a little 10 larger than the neckband and two narrow spaced arms 29 whose outer edges are straight and parallel. The sides of the shirt are folded back around these arms and the shirt tails are folded back and up around 15 their ends. The cuffs may be folded in or allowed to project from the neckband end or sides of the shirt as desired. The shirt thus folded is pinned in place in the usual manner but the form body 28 projects 20 slightly from the end of the shirt, as shown in Fig. 3, and the straight outer edges of arms 29 maintain the side edges or folds of the shirt straight and parallel, as will be readily understood.

25 The shirt is then laid on the pressing table of the machine and a neckband former or expander, of proper size, is introduced into its neckband opening. This former may be of any suitable shape and form and, as 30 shown, is a self contained portable device which is connected to a part of the machine in use but is not permanently attached thereto. It comprises two members 30 and 31 slidably connected by guide pins 32 and 35 normally held expanded by the springs 33. By pressing the parts together the former 40 can be readily introduced into the neckband and expands to fill the same. One of the parts of the former, such as part 31, is provided with suitable means, such as the 45 holes 34, to receive pins 35 on an arm 36 loosely pivoted upon a shaft 37 carried in the bearings on the body member 15. When the shirt is laid in position this arm is 50 brought down to engage the pins in the holes, which correctly and exactly locate the shirt on the board so as to be in proper position to be pressed, relative to the recess 8, when the board is moved to co-operative 55 relation with the stationary pressing member. Upon the shirt is then placed a press plate 38, which is a thin metal plate having one end cut out in U shape to fit around the shirt neckband. This plate is preferably a 60 loose part laid by hand on the shirt and is large enough to completely cover all the exposed surface of the shirt. Said plate is then pressed down against the neckband end of the shirt to clamp said end of the shirt 65 securely to the board. This is accomplished by two arms 39 having end extensions 40 projecting laterally over the edges of the plate, and which arms are carried by the shaft 37. Said shaft is provided with an arm 41 connected through the compres-

sion spring 42 to a link 43 pivotally connected to an arm 44 carried by a shaft 45 which may be oscillated by an operating arm 46. By pushing back on said operating arm the extensions 40 are forced down on the 70 plate by yielding pressure to clamp the shirt. Arm 46 carries a pivoted latch 47 whose inner end travels over a stationary curved abutment 48 and in clamping position drops in behind a stop projection 49 75 thereon, from which it may be released by pressing the pivoted release lever 50 whose lower end depresses a sliding pin 51 engaging the outer end of the latch 47.

In the form shown in Fig. 1, the plate 38 80 has lateral extensions 38^a which are introduced into wide slots 39^a in the arms 39, so that the plate is carried by the arms and need not be removed therefrom, but is merely lifted up from the shirt by tilting the 85 arms 39. The wide slots 39^a enable the plate to have an equalizing movement relative to arms 39 in moving to parallel clamping position on the board. Fig. 6 shows another arrangement in which the plate 38 is 90 free of connection to the arms 39 and is bodily removed from the board each time a shirt is removed therefrom and is reapplied to the next shirt to be pressed.

The shirt, having been clamped at its 95 neckband end, as described, is now stretched longitudinally. For this purpose a stiff flat blade or bar 52, which may be a narrow sheet metal strip, is passed through the folded tail of the shirt, said bar being of a 100 length such that its ends project beyond the lateral edges of the shirt board. The ends of said bar are engaged by the hooked ends 53 of sliding rods 54 carried by arms 55 on a shaft 56. Compression springs 57 hold 105 the hooks 53 yieldably down toward the board but allow them to move when the shaft 56 is oscillated. Each arm 55 is connected by a pivoted link 58 to a short arm 59 on a shaft 60 which may be oscillated by 110 a lever 61 whose outer end 62 is threaded into its body 63 and may be turned to force a shoe 64 against an abutment 65 to clamp and hold the parts in any adjusted position, thereby holding the stretching tension applied to the shirt.

When the shirt is fully dressed and stretched on the board, as described, the lock release treadle 24 is depressed and the frame 12 is rotated in the direction of the 115 arrow A, Fig. 1, to bring the dressed board into position beneath the heated head. The locking device 23 engages the frame and locks it in its new position. If either the arm 36 or the arms 39 have been left in 120 raised position either accidentally or for any other reason, said arms engage one or the other of the rollers 11 in moving to new position and are depressed thereby, so that 125 no damage to the machine can occur. When 130

the board is in its new position the plunger 19 is elevated to bring the board and shirt into pressing relation with the heated head, during which movement the arm extensions 5 40 enter the recesses 9 of the heated press head. The shirt need not be moistened and no steam need be applied to it, but the ironing pressure maintained for a sufficient period, say thirty seconds, will iron out all 10 wrinkles and produce a neat smooth appearance over the entire shirt. The release of the shirt from the clamping and ironing devices requires no description.

The machine is of simple form, can be 15 readily operated, and has a large output. It materially reduces the cost of ironing negligee shirts and improves their appearance.

What I claim is:—

20 1. A skeleton form on which shirts are dressed while pressing the same in a pressing machine, said form having a base or body portion adapted to lie under the shirt yoke and parallel side edge portions, the 25 central portion of said form being open.

20 2. A pressing machine, comprising relatively movable upper and lower pressing members, a skeleton form on which the shirt is dressed, said form having an open central 30 portion and parallel side edges substantially co-extensive with the length of the exposed bosom portion of the shirt, a plate applied to the exposed face of the shirt, means for clamping the neckband end of said plate 35 to the lower pressing members, a neck band former, and means engaging said former from above the same for holding it in position on the lower pressing member.

40 3. A pressing machine, comprising relatively movable upper and lower pressing members, a skeleton form on which the shirt is dressed, said form having an open central portion and parallel side edges substantially co-extensive with the length of the exposed 45 bosom portion of the shirt, a plate applied to the exposed face of the shirt, means independent of the upper pressing member for clamping the neckband end of said plate to the lower pressing member, means for stretching the shirt from its other end, a 50 neckband former, and means engaging said former from above the same for holding it in position on the lower pressing member.

45 4. A pressing machine, comprising an ironing bed having an uninterrupted work receiving surface, means for locating a shirt comprising an arm movable relative to said bed and in operative position lying above 55 said bed and in a definite location relative

thereto and a self-contained neckband former 60 adapted for releasable connection with said arm and when connected thereto to locate a shirt on the bed, and a co-operating pressing head having a recess adapted to register with said neckband former when the latter is connected to said arm and lying in 65 position on said bed.

5. A pressing machine, comprising an ironing bed having an uninterrupted work receiving surface, means for locating a shirt 70 comprising an arm movable relative to said bed and in operative position lying above said bed and in a definite location relative thereto and a self-contained neckband former 75 adapted for releasable connection with said arm and when connected thereto to locate a shirt on the bed, a co-operating pressing head having a recess adapted to register with said neckband former when the latter is connected to said arm and lying 80 in position on said bed, and a self-contained flexible ironing plate having a recess to receive the neckband former and adapted to be manually registered therewith.

6. A pressing machine, comprising an ironing bed having an uninterrupted work receiving surface, means for locating a shirt comprising an arm movable relative to said bed and in operative position lying above 90 said bed and in a definite location relative thereto and a self-contained neckband former 95 adapted for releasable connection with said arm and when connected thereto to locate a shirt on the bed, a co-operating pressing head having a recess adapted to register with said neckband former when the latter is connected to said arm and lying 100 in position on said bed, a self-contained flexible ironing plate having a recess to receive the neckband former and adapted to 105 be manually registered therewith, and means for clamping the neckband end of said plate to said board to enable the shirt to be stretched from its tail end.

7. A pressing machine, comprising relatively movable pressing head and bed members, the bed member being adapted to receive a garment to be pressed and provided with an operating member movable to operative and inoperative positions, and means 110 on the head member adapted upon relative movement between the head and bed members to move said operating member to operative position.

In testimony whereof I affix my signature.

DANA H. BENJAMIN.
